SLIPPER OR SIMILAR ARTICLE

Kyoichi Miyachi and Saburo Fujii, Fukuyama-shi, Japan,
assignors to Hiroshima Gomu Kogyo Kabushiki Kaisha
(Hiroshima Rubber Industrial Co., Ltd.), Fukuyama
City, Japan

Application January 27, 1956, Serial No. 39,939

Claims priority, application Japan December 28, 1955
Term of patent 14 years

(Cl. D7—7)

Fig. 1 is a top plan view of a slipper showing our new design,

Fig. 2 is a side view,

Fig. 3 is a bottom plan view, and

Fig. 4 is a perspective view thereof.

The characteristic feature of our slipper design resides in the combination on the slipper disclosed of the specific patterned upper surface in association with the textured bottom surface and the decorated strap members, all as shown.

We claim:

The ornamental design for a slipper or similar article, as shown and described.
